COVER FOR GAS RANGE BURNER
COMPARTMENTJoseph Beevar, Wickliffe, Ohio, assignor to The
Cleveland Cooperative Stove Company, Cleve-
land, Ohio, a corporation of Ohio

Application December 11, 1934, Serial No. 757,009

3 Claims. (Cl. 126—37)

This invention relates to a compartment cover and particularly to a cover for use in connection with top burner compartments of gas cooking ranges.

5 One of the principal objects of the invention is to provide a cover for this purpose which may be swung from the wall which it covers into a position substantially parallel to and in face to face relationship to one of the other contiguous 10 walls of the compartment.

15 A more specific object is to provide a cover for a burner compartment which is open at the top, the cover being disposed horizontally, when in closing relation to the compartment, and being 20 mounted through a connection with the rear wall of the compartment or range so that upon swinging the cover upwardly toward an upright position by lifting at the front edge, the cover will move rearwardly and downwardly concurrently 25 with the upward swing and into an upright position in the rear of the range or compartment, either with a predetermined portion projecting above the level of the plane of the open top of the burner compartment or with the entire cover lying below such level.

30 Another object is to effect this operation while maintaining the movement of the rear edge of the cover in a path close to the rear of the range so that no greater clearance is required between the rear of the range and the wall of the room in which it is disposed than is usually required for gas line connections to the range.

35 Other objects and advantages will become apparent from the following specification wherein reference is made to the drawings in which,

Fig. 1 is a perspective view of a cover and mounting therefor embodying the principles of the present invention;

40 Figs. 2 and 3 are sectional views taken on planes indicated by the lines 2—2 and 3—3 respectively of Figs. 3 and 1, respectively, showing the cover in closed position; and

Fig. 4 is a sectional view corresponding to Fig. 3 but with the cover in an open position.

45 For purposes of illustration, the cover is shown associated with a gas range 1, indicated by the dot-dash line in Fig. 1, which range is provided with a burner compartment 2a which is open at the top to permit access to the burners 2, the 50 top wall of the compartment and opening being substantially horizontal. The cover 3 is of sufficient size to completely cover the open portion of the top wall of the compartment 2a when the cover is disposed in horizontal position.

55 In order that the cover may be readily moved

from its closing position and disposed out of the way, it is provided near its rear margin with suitable means such as brackets 4 which receive the ends 5a of a connecting element 5, the ends 5a being turned parallel to the rear edge of the 5 cover and pivotally received in the brackets 4. Thus the pivotal axis of this connection between the connecting element 5 and the cover 3 is horizontal and parallel to the rear edge of the cover 3.

Another portion of the connecting element 5, 10 indicated at 5b, is pivotally connected to a support 6, carried by the range in a manner to be described hereinafter, the pivotal axis of the connection to the support 6 being parallel to and spaced from the first mentioned pivotal axis. 15

Thus the cover is secured to the range through the medium of a double hinge connection provided by the element 5.

The double hinge structure itself has been used heretofore for covers for various types of compartments in which it was desirable not only to swing the cover upwardly to an open position but also to dispose the cover to the rear or side of the compartment with which associated and in substantially face to face relationship to one of 25 the walls of the compartment contiguous to the open wall. It is readily apparent, however, that in swinging the cover to an upright position through the medium of such a connection, the proportion of the cover which is disposed below 30 the level of or to one side of the plane of the open wall is limited to twice the distance between the pivots 5a and 5b. If the cover were long in a direction transversely of the pivotal axis, that is, fore and aft in the form illustrated, and all 35 or a large portion of it were to be disposed below the level of the top of the compartment, considerable clearance would be necessary between the rear of the range or compartment and the wall of the room in which the same were disposed 40 to accommodate passage of the rear edge of the cover therebetween as it moved rearwardly in an arcuate path about the pivot 5b.

In order to provide for better movement of the cover so as to dispense with this clearance 45 limitation, the support 6, heretofore mentioned, is provided, the support being mounted for movement toward and away from the plane of the top of the compartment. A convenient mounting for the support 6 may comprise parallel spaced 50 guide rails or rods 7 which are secured in slightly spaced relation to the rear wall of the compartment or range, as illustrated in Fig. 1. The rods preferably extend vertically and parallel to the plane of the rear wall of the range, but may be 55

placed at an angle to the rear wall, depending on the movement desired. The ends of the support 6 are provided with guide ways 8 which slidably receive the rods 7 so that the support may move therealong concurrently with the operation of the double hinge connecting element 5.

In order to partially counterbalance the weight of the cover 3, a tension spring 9 is secured at one of its ends to the support 6 and is anchored 10 at its other end in fixed relation to the range.

Referring to Fig. 3, it will be noted that each of the guide rails 7 is provided with a series of spaced transverse holes 10 through which a suitable pin may be passed for securing stop cushions 11 in desired positions therealong and thus limit the downward movement of the support 6. The rails 7 are preferably of sufficient length so that, if desired, the support 6 can be lowered to a position wherein the entire cover can be dropped out 20 of sight.

In order to assist in guiding the cover as it is moved about the pivotal axes at 5a and 5b and with the support, it is provided on its under face, along the side margins, with inturned flanges 12 which form tracks operatively engaging rollers 13 mounted on brackets 14 at the rear of the compartment.

Referring to Figs. 1, 3 and 4, it is apparent that as the cover is swung upwardly by lifting on the handle 15 in the usual manner, the cover swings upwardly about the pivotal axis at 5a and concurrently with the movement about the pivots 5a, the pivots 5a themselves swing rearwardly and downwardly about the pivot 5b, and concurrently 35 with these two movements, the support 6 moves vertically downwardly so that the cover moves properly as a result of concurrent pivotal movements and lineal movement. The overbalance of the cover, after partially opened, is sufficient to 40 cause it to travel to fully open position against the pull of the spring 9.

In the position illustrated in Fig. 4, the cushions 11 have been shown as positioned so that a small portion of the front edge of the cover protrudes 45 above the plane of the open top of the compartment to form a splash guard but it is readily apparent that by positioning the cushions at the bottom of the rails 7, the entire cover can be disposed in upright position in substantially face to 50 face parallel relation to the rear wall of the range and with its front edge disposed substantially at the plane of the open top wall of the compartment. While in this position, a slight forward pull on the handle 15 causes the cover to move upwardly and forwardly with the front edge swinging 55 downwardly concurrently so that the cover moves into closing position on the compartment, the overbalance of the cover, after partially closed, being sufficient to cause it to swing to fully closed 60 position.

Having thus described my invention,

I claim:

1. In a cooking range having a burner com-

partment open at the top, a horizontally disposed cover closing said compartment at the top, a connecting element pivotally connected to the cover, the pivotal axis of said connection extending horizontally and parallel to the rear edge 5 of the cover, a support carried by the range at the rear face thereof, means mounting said support for travel in a substantially vertical lineal path toward and away from the plane of said top opening, said connecting element being pivotally connected to said support, the pivotal axis of said last mentioned connection being spaced from and parallel to the first mentioned pivotal connection, and means cooperable with the cover for guiding the cover in a predetermined path of travel from 15 horizontal to upright position at the rear of the range during concurrent pivotal operation of the connecting element about both pivotal axes and concurrent travel of said support.

2. In a cooking range having a burner compartment open at the top face, a rigid cover for said compartment, a connecting member pivotally connected to the cover near the rear margin, the pivotal axis of the connection extending horizontally and parallel to the rear edge of the cover, 25 an upright guide track carried by the range, a support slidable vertically along said track and pivotally connected to the connecting member, the pivotal axis of the last mentioned connection being spaced from and parallel to the first mentioned pivotal axis, and adjustable abutment means cooperable with the support for limiting the downward movement of the support, whereby the cover may be moved from a horizontal position to a vertical position and disposed with its 35 front edge in a predetermined desired vertical position relative to the plane of the opening.

3. In a cooking range having a burner compartment open at the top, a horizontally disposed cover closing said compartment at the top, a connecting element pivotally connected to the cover, the pivotal axis of said connection extending horizontally and parallel to the rear edge of the cover, a support carried by the range at the rear face thereof, means mounting said support for travel 40 in a substantially vertical lineal path toward and away from the plane of said top opening, said connecting element being pivotally connected to said support, the pivotal axis of said last mentioned connection being spaced from and parallel 45 to the first mentioned pivotal connection, and means cooperable with the cover for guiding the cover in a predetermined path of travel from horizontal to upright position at the rear of the range during concurrent pivotal operation of the connecting element about both pivotal axes and concurrent travel of said support, and spring means 50 operatively connected to said support and to the range for partially counterbalancing the weight of the cover when the cover is moved to a vertical position.

JOSEPH BECVAR.
